UNITED STATES PATENT OFFICE.

HENRY GRABACH, OF CLYDE, OHIO.

SHOE.

SPECIFICATION forming part of Letters Patent No. 244,588, dated July 19, 1881.

Application filed April 25, 1881. (No model.)

To all whom it may concern:

Be it known that I, HENRY GRABACH, of Clyde, Sandusky county, Ohio, have invented an Improvement in Shoes, of which the following is a specification.

The invention consists in a counter-stiffener arranged on the inside of the ordinary lining of the counter and fastened to the latter in order to avoid the wrinkling and wear of the lining. The stiffener is ordinarily placed between the counter and its lining, being stuck and not fastened at the top, so that the lining is often worn through and the heel allowed to catch on the stiffener and thereby break it down; but even before this occurs the lining settles down, becomes wrinkled, and is very disagreeable to the wearer.

In the drawing, a shoe is exhibited in side elevation, the rear part being in section to show my improvement.

A represents the stiffener of the shoe B; and C the usual lining, which, in this instance, is

stitched to the upper edge of the counter, while the stiffener A covers its other face and is also stitched or otherwise secured to the upper portion of the counter, thus inclosing the lining between the stiffener and the counter where it is protected from wear and prevented from wrinkling.

Having thus described all that is necessary to a full understanding of my invention, what I claim as new is—

An improvement in the manufacture of boots and shoes, which consists in securing the counter-stiffener to the shortened lining by a line of stitches around its edge, the lining of heel portion terminating at such edge-connection, whereby the friction of the heel of the foot comes upon the stiffener and a portion of the usual lining is saved.

HENRY GRABACH.
